United States Patent Office

Des. 198,184
Patented May 12, 1964

198,184

DECORATIVE COLUMN

Edward J. Kusel, 2343 Ridgewood Road, and Robert S. Mankin, 167 Overwood Road, both of Akron, Ohio

Filed June 3, 1963, Ser. No. 75,186

Term of patent 14 years

(Cl. D54—2)

We claim:

The ornamental design for a decorative column, as shown.
